UNITED STATES PATENT OFFICE

2,269,314

ELECTRICAL CONNECTOR

Rob Roy Macdonald, Bayside, N. Y.

Application May 23, 1941, Serial No. 394,793

3 Claims. (Cl. 173—332)

This invention relates to electrical connectors, or switches, of the type wherein two body members having complementary terminal plug and resilient socket elements are employed, which elements are releasably held in operative relationship. A form of connector of this type is disclosed in United States Patent No. 1,956,037, dated April 24, 1934.

An object of the invention is to improve the construction of the prior connector in order to reduce the cost of manufacture thereof, to ensure a more flexible and effective electrical contact between the complementary terminal elements than formerly, and to facilitate the engagement and disengagement of said elements as occasion may require.

Another object of the invention is to reduce to a minimum the liability of destructive arcing contact of the opposing elements during their association and separation, thus prolonging the effective life of the connector, or switch, when it is subjected to repeated circuit interruptions.

With these and other objects in view my invention comprises features of novelty which will be hereinafter described, the scope of the invention being expressed in the appended claims.

In the drawing—

Figure 1 is a perspective view of a closed connector embodying my invention.

Fig. 2 is a longitudinal vertical section of the structure, as on the line 2—2 of Fig. 1.

Fig. 3 is a longitudinal horizontal section thereof, as on the line 3—3 of Fig. 2.

Fig. 4 is a sectional detail of the telescoping ends of the plug and socket elements, showing the clamping sleeve in initial abutting relation to the resilient members of the socket.

Fig. 5 is a sectional detail of one of the blocks of the connector showing locking means for the confined end of the terminal bar, as on the line 5—5 of Fig. 3.

Referring to the drawing, 10 and 11 designate complementary terminal bars of conducting material, preferably cylindrical in cross-section, which bars are fixedly held in the bores 12 and 13 of two bodies or blocks 14 and 15, respectively, of insulating material. These blocks are suitably recessed, at their outer ends, as at 16, for the passage of the leads 17 of a power line and the current carrying leads 18 to the bars 11 and 10, respectively. The leads are electrically connected to the terminal bars as hereinafter described.

Each of the terminal bars 10 is circumferentially reduced to form a plug 19 which extends beyond the inner end of the block 14 and terminates

in a substantially semi-spherical head portion 20, constituting a male contact member; and each of the bars 11 is circumferentially reduced (as at 21), longitudinally bores (as at 22) and slotted (as at 23) to provide a female member having resilient members 24 of less diameter than the bore 13 and preferably terminating inwardly of the adjacent end of the block 15. The normal diameter of the bore of the socket element is equal to that of the head 20, or substantially so, in order to permit the free telescopic entry of the head into the socket element until the associated blocks 14 and 15 have been relatively moved into close contact one with the other, as will presently appear.

The reduced portion 21 of the bar 11 is short of the free extremity of the bar, thus presenting a furcated circumferential contact portion 25. This portion is suitably bevelled at its outer end, thus providing a divided cam face 26. That portion of the bore in the block 15 surrounding the contact portion 25, is enlarged, as at 27, to afford a recess for the free entry thereinto of the projecting portion 28 of a sleeve 29 which is affixed to and forms in effect an integral part of the terminal bar 10. The internal diameter of the projecting portion of the sleeve is slightly less than the external diameter of the opposing contact portions 25 of the socket members 24, the extremity of the sleeve being bevelled to present a cam surface 30 which, immediately preceding the complete entry of the plug in the socket element, impinges against the annular cam surface 26 presented by the resilient members of the socket element, as seen in Fig. 4.

The angularity of the cam surface 30 on the sleeve is less than that of the divided cam surface 26 of the socket element, so that in the closing of the electric circuit by the connector the sleeve cam initially bears against the outer edge 31 of the socket cam 26, thus bowing the socket members radially inward and in intimate contact with the plug head 20, and thereafter progressively overlapping the contact portion 25 of the socket element and maintaining effective electrical contact therewith. By virtue of the described bowing of the socket members the electric contact between the sleeve and the socket element is effected only at the inner or higher edge 31 of the socket cam, thus presenting an annular contact of small area. Similarly by virtue of the relative angularity of the cam surfaces 30 and 26 of the sleeve and socket members, respectively, an annular contact of small area is effected, as indicated in Figs. 2 and 3. Likewise a

small contact area is established between the inner surfaces of the socket members and the rounded head 20 of the plug, as indicated at 32, since such members are spaced from the shank of the plug when the parts are in engaged relationship.

From the foregoing it will be seen that the head 20 serves as a support or fulcrum for the resilient socket members during the closing of the terminal blocks, and that, apart from the contact areas indicated at 31 and 32, the resilient socket members are out of electrical contact with the body of the plug and the sleeve, which spaced contact is maintained throughout the locking movement, thus ensuring the elasticity of the members between their free ends and the fulcrum head. Consequently the members are uniformly and positively moved in contact with the inner surface of the sleeve without jamming such members between the sleeve and the shank of the plug; it being noted that when, by virtue of such non-jamming condition during the closing force on the blocks, the sleeve overcomes and initially overlaps the opposing ends of the resilient members, said blocks are abruptly moved into close end to end contact. In the resulting absence of extended metal to metal contact areas, all liability of arcing contact between the telescopic elements during their engagement or disengagement, is reduced to a minimum. Moreover, in the event of the internal burning of the extremities of one or more of the resilient members of the socket element, on account of repeated interruptions of the electric circuit, such members, owing to the clearance between them and the shank of the plug, will be forced by the sleeve 29 in intimate electrical contact with the head of the plug, and this without jamming of the elements. It will also be seen that the forcible bowing of the female members under opposing pressure against the exterior edge and the interior wall of the plug head 20 and the sleeve 29, respectively, not only insures efficient electrical contact at the respective points of contact, but also holds the bodies or blocks firmly yet detachably in close relation without the use of external locking devices.

The hereinbefore described construction and co-operative relation of the terminal elements, by virtue of the resulting flexibility of the assembly, permits greater tolerance in the dimensions of the connector than formerly, thus materially reducing the manufacturing cost.

As a simple and efficient means to lock the terminal bars 10 and 11 in their respective blocks, and to prevent the accidental withdrawal of the bars, the inner end portion of each of the bars is reduced transversely, as at 33, to form a recess in communication with a vertical bore 34 in the block, the floor of the recess being bored and tapped, as at 35, for the reception of the terminal screw 36 for the lead. Before the entrance of the screw a suitable washer 37 is driven tightly into the recess, which washer in conjunction with the opposing wall of the bore 34, thus effectually prevents the accidental withdrawal of the bar until the screw and washer are removed, and also provides an increased contact area for the lead. The mouth of the vertical bore 34 is closed by a reinforcing plate 38 which is fixedly held by screws 39 in a transverse recess in the top of the block, suitable insulation 40 being interposed between the block and the plate.

I claim:

1. A connector embodying terminal members having telescopic male and female elements, the male element comprising a shank having a head 5 at the free end thereof of greater diameter than the shank, and the female element comprising longitudinally-extending resilient members having an internal diameter substantially equal to the maximum diameter of said head, said resilient members having at their free ends external projections, and a projecting annular member 10 mounted with the male element adapted to receive the free ends of the resilient members and having at its outer or free end a cam surface 15 to co-act with the opposing ends of said resilient members and thereby force said external projections toward yet free from the said shank and in electrical contact with the inner surface of the annular member, the bodies of the said resilient members by the resulting bowing thereof being pressed hard against the said head in opposition to the resistance of the external projections of said resilient members by the inner wall of said annular member.
2. A connector embodying terminal members having telescopic male and female elements, the male element comprising a shank having a head 20 at the free end thereof of greater diameter than the shank, and the female element comprising 30 longitudinally-extending resilient members having an internal diameter substantially equal to the maximum diameter of said head, said resilient members having at their free ends external projections, and being beveled to provide a divided cam surface, and a projecting annular member 35 mounted with the male element adapted to receive the free ends of the resilient members and having its outer or free end beveled to provide a cam surface of different angularity from that of the first-named cam surface so as to present a small contact area between the two cam surfaces and thereby co-act to force said external projections toward yet free from the said shank and in electrical contact with the inner 40 surface of the annular member, the bodies of the said resilient members by the resulting bowing thereof being pressed hard against the said head in opposition to the resistance of the external projections of said resilient members by the inner wall of said annular member.
3. A connector embodying terminal members having telescopic male and female elements, the male element comprising a shank having a head 50 at the free end thereof of greater diameter than the shank, and the female element comprising longitudinally-extending resilient members having an internal diameter substantially equal to the maximum diameter of said head, said resilient members having at their free ends external 55 projections, and a projecting annular member mounted with the male element adapted to receive the free ends of the resilient members, and cam means adapted to press the free ends of the resilient members toward each other as they enter the annular projecting member to force the free ends of the resilient members over the head and yet free of the shank of the male element, the bodies of said resilient members by the resulting bowing thereof being pressed hard 60 against the said head in opposition to the resistance of the external projections of said resilient members by the inner wall of said annular member.
